CLAIM

The ornamental design for a car wash brush, as shown and described.

DESCRIPTION

FIG. 1 is a perspective view of a car wash brush, showing my new design;

FIG. 2 is another perspective view thereof;

FIG. 3 is a front elevation view thereof;

FIG. 4 is a rear elevation view thereof;

FIG. 5 is a left side elevation view thereof, the right side elevation view being a mirror image of FIG. 5;

FIG. 6 is a top plan view thereof;

FIG. 7 is a bottom plan view thereof;

FIG. 8 is a partial enlarged view of FIG. 1; and,

FIG. 9 is a partial enlarged view of FIG. 2.

1 Claim, 6 Drawing Sheets
